UNITED STATES PATENT OFFICE

2,088,404

STAPLING PLIERS

Earl C. Bunnell, Stratford, Conn., assignor to
 Neva-Clog Products, Inc., Bridgeport, Conn.,
 a corporation of Connecticut

Application September 14, 1934, Serial No. 743,988

9 Claims. (Cl. 1—49)

The present invention relates to stapling pliers of the type adapted to separate individual staples from a staple strip and drive and clinch the staple with respect to the material to be stapled. In stapling pliers and other stapling devices heretofore in use the staples were apt to become clogged due for the most part to incompleteness of the driving stroke, in which case the partially driven staple would remain in the device while the driving mechanism returned to position to drive the next staple, with the result that the staples would then become clogged. Obviously the clogged staple tended to damage the device and its removal was both difficult and inconvenient. In some instances special means have been built into the stapling device for the purpose of removing the clogged staples.

It is an object of the present invention to provide a stapling device in which the possibility of clogging the staples is removed, and to this end I propose to provide a locking mechanism which will necessitate complete operation of the staple driving means, once the stapling operation has begun, before the driving mechanism can again become operative to drive another staple. Another object is to provide a stapling plier of very compact form, free from projecting or exposed moving parts, so that the same may be conveniently carried in the pocket or in a brief case. A further object is to provide a mechanism of extreme simplicity, which will not readily get out of order, and which may be easily disassembled for the purpose of repair or replacement of parts.

Another object is to provide a stapling plier having a relatively deep mouth for receiving the material to be stapled to the end that the staples may be inserted at a considerable distance from the edge of the material.

With the above and other objects in view an embodiment of the invention is shown in the accompanying drawing, and this embodiment will be hereinafter more fully described with reference thereto, and the invention will be finally pointed out in the claims.

In the drawing:

Fig. 1 is a side elevation of a stapling plier, according to the exemplary illustrated embodiment of the invention.

Fig. 2 is a vertical longitudinal sectional view. Fig. 3 is a transverse vertical sectional view of the staple guide casing taken along the line 3—3 of Fig. 2.

Fig. 4 is a transverse vertical sectional view, taken along the line 4—4 of Fig. 2.

Fig. 5 is a transverse vertical sectional view, taken along the line 5—5 of Fig. 2.

Figs. 6, 7 and 8 are fragmentary vertical sectional views showing various operative positions of the staple driving mechanism.

Fig. 9 is a horizontal sectional view, taken along the line 9—9 of Fig. 2, and

Fig. 10 is a perspective view of the locking slide member employed.

Similar reference characters indicate corresponding parts throughout the several figures of the drawing.

Referring to the drawing, the stapling pliers, according to the exemplary embodiment of the invention illustrated therein, comprises a housing 10 preferably formed of formed up sheet metal, having the upper grip-handle 11 formed integrally therewith, the lower portions of the side walls of the housing having slots 12—12 constituting the inner end of the material receiving mouth, the portions 13—13 of the side walls below these slots having the anvil member 14 secured between them as by spot-welding, and these portions 13—13 and the anvil member constituting the lower jaw of the pliers. The anvil member is of channel form, and at its forward end has a staple bending pocket or recess 15 pressed therein.

The forward edges of the side walls of the housing above the slots 12—12 are of arcuate form, as at 16—16, the arc being concentric to the pivot pin 17 secured between the side walls, and upon which the upper jaw and staple driving lever are pivotally mounted, as will presently more fully appear. At the upper ends of the arcuate edges 16—16 the forward edges of the side-walls extend vertically as at 18—18 to form limit stop portions.

The upper jaw and staple carrying guide of the plier is of box-like form and comprises a member 19 of U-form in cross-section, its transverse portion forming the base wall of the box, a member 20 also of U-form in cross-section, but inverted, and disposed between the side walls of the member 19 with its forward edges inwardly offset from the forward edges of the member 19, its transverse portion constituting the top wall of the box, and a member 21 also of U-form in cross-section but disposed laterally with its side walls at the outer sides of the side walls of the member 19, its transverse wall abutting the forward edges of the member 19 and being slightly spaced from the forward edges of the member 20 and constituting the front wall of the box. The spacing of this front wall from the member 20 forms a vertical guide passage 22 for the staple 55

driver, as will hereinafter more fully appear. The forward edge of the transverse portion of the member 19 is cut back, as at 22^a, to form an outlet passage for the staples in line with the 5 passage 22. The three members 19, 20 and 21 are secured together by riveted cross-pins 23, 24 and 25. The rearward edges of the members 19, 20 and 21 are shaped, as at 26, to conform to the forward edge portions 16 and 18 of the housing 10.

At its lower end the member 19 is provided with a rearwardly extending elongated channel extension portion 27 for receiving the staple strip and staple feeder. A staple carrier bar 28 of 15 U-shape in cross-section is secured to the base of the member 19 and its extension portion 27, its forward edge being flush with the inner edge of the passage 22 formed by the forward edge of the member 20. The side walls of the carrier 20 bar 28 are slightly spaced from the side walls of the member 19 and the extension 27, and the top 25 edges are slightly spaced from inwardly bent flanges 29—29 provided at the upper edges of the side walls of the extension 27, thereby providing right angular guide spaces at each side in which the inverted U-shaped staple strip A is guided, as clearly shown in Figs. 3, 4 and 5. The lower edges of the side walls of the member 20 are provided with inwardly bent flanges 30—30 30 in alignment with the flanges 29—29 and forming continuations of these flanges for guiding the staples up to the passage 22. A pair of upwardly bent apertured ears 31—31 are formed on the flanges 29—29 and engage the pin 17 to thus 35 pivotally mount the upper jaw and staple carrying member.

The staple strip, as seen in Fig. 2, is pressed forwardly, so that the first staple is disposed in the passage 22, by means of staple feeder 32 of 40 inverted U-shape in cross-section mounted on the bar 28 and having a pair of apertured lugs 33—33 disposed within the channel of the bar 28 and slidably engaged by a rod 34 having a head 35 at its inner end disposed at the forward side of 45 the forward lug 33, a spiral spring 36 being disposed about the rod between the rearward lug 33 and a locking plate 37 secured upon the outer end of the rod. This locking plate has a finger gripping extension 38 at its base and at one side 50 is provided with a lug 39 adapted to be turned into locking engagement with a shouldered notch 40 provided in the side wall of the extension 37. By turning the lug out of locking engagement 55 with the notch the staple feeder may be removed for the purpose of inserting another strip.

The staple driving lever 41 is provided with a lower grip handle 42 and is pivotally mounted on the pin 17 between the side walls of the housing 10. This lever is preferably formed of sheet 60 metal, the two side portions of the lever being folded upwardly from the grip-handle portion, and the forward end portions of the sides being secured together, as by spot-welding, to form a 65 driver-actuating bolt portion 43, the forward end of which engages the slot 44 of the staple driver 45 disposed in the passage 22 and projects through a slot 46 formed in the transverse front wall portion of the member 20.

70 The upper edge of the bolt portion 43 is straight and normally engages the cross pins 23 and 25, being pressed into such engagement by a spring 47 connected between a hook 48 formed on the grip handle 42 and a hook 49 formed on the anvil member 14, and pressing the upper jaw into

abutting relation with the limit stop edge portions 18 of the housing 10. A hair-pin spring 50 has one end secured, as at 51, to the base of the extension 27 and its other end engaged with the grip handle 42 and exerts pressure on the handle 5 42 and its bolt portion 43 in clockwise direction about the pivot pin 17, and pressure on the extension 27 and the member 21 and cross pins 23 and 25 carried thereby in counter-clockwise direction, whereby the cross-pins 23 and 25 of the 10 driver housing are normally pressed into engagement with the bolt portion 43, as shown in Fig. 2.

Upon the bolt 43 there is mounted a locking member comprising an upper transverse portion 52 engaged with the upper edge of the bolt and 15 side portions 53 and 54 disposed at each side. The side portion 53 is provided at its forward edge, which is flush with the forward edge of the upper portion 52, with an inwardly bent lug 55 projecting beneath the lower edge 56 of the forward end portion of the bolt portion 43, this edge portion 56 being parallel to the upper edge of the bolt portion 43, and which lug 55 is adapted in a retracted position of the locking member, as will presently more fully appear, to enter a notch 57 25 provided in the edge of the bolt portion 43 at the inner end of the edge portion 56. The side portion 54 projects forwardly of the upper portion 52 so that its upper edge is normally beneath the cross-pin 23 and flush with the upper edge of 30 the bolt, and at its lower edge is provided with a 45° angle cam surface 58 outwardly offset from the lug 55, and adapted, as will presently more fully appear, to cooperate with the cross pin 24. Slots 59—59 are provided in the respective side 35 portions 53 and 54 which are engaged by the ends of a pin 60 secured in the bolt 43. Hair-pin springs 61—61 having their coil portions mounted on the ends of the pin 60 have one end engaged beneath a pin 62 secured to the bolt 43 and the 40 other end engaged behind lugs 63—63 bent outwardly from the side portions 53 and 54. These springs normally press the locking member forwardly Fig. 10 and at the same time in clockwise direction about the pin 60 to press the lug 55 45 against the lower edge portion 56 of the bolt.

The operation is as follows:—

As shown in Fig. 2 the lower edge of the staple driver 45 is directly above, but slightly spaced from a staple to be driven, the upper edge of the 50 forward end of the bolt 43 is engaged with the cross-pin 23, and the locking member is retained in retracted position through engagement of the forward edge of its upper portion 52 with the pin 23, the spring 61 exerting a forward pressure 55 thereon, but not enough to overcome the retaining force of the spring 50. The material B to be stapled is placed between the plier jaws and the grip handles are pressed together, first bringing the upper jaw downwardly to grip the material, 60 and then causing the bolt 43 to move the staple driver 45 downwardly in the groove 22, severing a staple from the staple strip and driving it toward the material. This action is insured through the fact that resistance offered by the 65 spring 47 to relative movement between the grip handles 41 and 42 is less than the resistance offered by the spring 50 to relative movement between the handle 42 and the staple carrying member 21 and its associated parts. As soon as 70 the bolt 43 is moved sufficiently to start the severing and driving of the staple the locking member is released and the forward edge of its portion 52 moves beneath the pin 23, as shown in Fig. 6. As long as it remains in this position 75

the bolt will be prevented from returning to its initial position, and the driver 45 will remain in the staple passage to prevent movement of another staple into place. This condition continues until the staple being driven is entirely cleared. Fig. 6 shows the staple driven almost clear and the bolt and driver allowed to retract to the position where the locking member prevents complete retraction, making it compulsory to completely clear the staple before complete retraction is possible, and as will now be explained.

As the cam surface 58 comes into engagement with the pin 24 the locking member starts to retract to move the lug 55 into relation with the retaining notch 57 of the bolt. As shown in Fig. 7 the staple is almost clear and the lug is about to enter the notch, and as shown in Fig. 8, the staple has cleared and the lug has entered the notch, the spring 61 snapping it into place. As the bolt returns to its normal position against the pin 23 the upper edge of the forwardly projecting end of the side portion 54 of the locking member first engages the pin 23 pressing the locking member in counter-clockwise direction to release the lug 55 from the notch 57 and permit the parts to again assume the position shown in Fig. 2, ready to drive another staple.

The staple pliers according to my invention are extremely simple in construction and operation, clogging of the staples is effectually prevented, and the possibility of breakage and wear of the parts greatly reduced. The guide passage 22 is accurately formed by the assembly of the members 19, 20, and 21, an extremely simple construction as compared to previous methods requiring machining of the guide passage. In order to repair or replace any of the parts, it is only necessary to remove the rivets 23, 24 and 25, which may be readily done by a service man. At the same time all of the parts are effectually enclosed and protected, so that they cannot be readily tampered with, or damaged by rough handling.

I have illustrated and described a preferred and satisfactory embodiment of my invention, but it will be obvious that changes may be made therein within the spirit and scope thereof, as defined in the appended claims.

Having thus described my invention, what I claim and desire to secure by Letters Patent is:—

1. In a stapling device, a staple strip guide, a staple driver, a lever engaged with said driver for imparting reciprocating movement thereto, abutment means including a portion normally engaged by said lever, a spring pressed locking member movably mounted on said lever adapted upon initial movement of said driver in staple driving direction to move relative to said abutment means to block complete return movement of said driver, cam means adapted during the staple driving movement of said driver to retract said locking member, retaining means adapted upon completion of the staple driving movement of said driver and complete retraction of said locking member to retain said locking member in retracted position to permit complete return movement of said driver, and releasing means adapted upon complete return movement of said driver to engage said abutment means to release said locking member from said retaining means.

2. In a stapling device, a stable strip guide, a staple driver, a lever engaged with said driver for imparting reciprocating movement thereto, abutment means including a portion normally

engaged by said lever, a spring pressed locking member movably mounted on said lever for sliding and rotary movement thereon adapted upon initial movement of said driver in staple driving direction to have projecting sliding movement into relation with said abutment means to block complete return movement of said driver, cam means adapted during the staple driving movement of said driver to retract said locking member, and retaining means adapted upon completion of the staple driving movement of said driver and complete retraction of said locking member to retain said locking member in retracted position to permit complete return movement of said driver, said abutment means adapted upon complete return movement of said driver to engage and rotate said locking member to release it from said retaining means.

3. In a stapling device, a staple strip guide, a staple driver, a lever engaged with said driver for imparting reciprocating movement thereto, abutment means including a portion normally engaged by said lever, a spring pressed locking member movably mounted on said lever for sliding and rotary movement thereon normally retained in partially projected position by said abutment means and adapted upon initial movement of said driver in staple driving direction to have complete projecting sliding movement relative to said abutment means to block complete return movement of said driver, cam means adapted during the staple driving movement of said driver to retract said locking member, and retaining means adapted upon completion of the staple driving movement of said driver and complete retraction of said locking member to retain said locking member in retracted position to permit complete return movement of said driver, said abutment means adapted upon complete return movement of said driver to engage and rotate said locking member to release it from said retaining means.

4. In a stapling device, a staple strip guide, a staple driver, a lever engaged with said driver for imparting reciprocating movement thereto, a pair of fixed spaced abutment means, one above and the other below said lever, said one abutment means including a portion normally engaged by said lever, a spring pressed locking member movably mounted on said lever for sliding and rotary movement thereon normally retained in partially projected position by said one abutment means and adapted upon initial movement of said driver in staple driving direction to have complete projecting sliding movement into relation with said one abutment means to block complete return movement of said driver, cam means on said locking member adapted during the staple driving movement of said driver to engage said other abutment means to retract said locking member, and retaining means adapted upon completion of the staple driving movement of said driver and complete retraction of said locking member to retain said locking member in retracted position through rotary movement of said locking member to permit complete return movement of said driver, said one abutment means adapted upon complete return movement of said driver to engage and rotate said locking member to release it from said retaining means.

5. In a stapling device, a casing comprising a member of U-shaped cross-section constituting a base wall and side walls, a second member of U-shape in cross-section constituting a front wall and side walls, a third member of U-shape in cross-

section constituting a top wall and side walls, the respective side walls of two of said members being engaged at each side of the respective side walls of the other member, means securing together said members, the forward edge of said base wall being recessed and constituting with the inner surface of said front wall a staple ejecting passage, a staple strip guide within said casing, and staple driving means within said casing adapted to drive a staple from said ejecting passage.

6. In a stapling device, a casing comprising a member of U-shaped cross-section constituting a base wall and side walls, a second member of U-shape in cross-section constituting a front wall and side walls, a third member of U-shape in cross-section constituting a top wall and side walls, the respective side walls of two of said members being engaged at each side of the respective side walls of the other member, means securing together said members, the forward edges of the intermediate side walls being engaged with the inner surface of said front wall, and the forward edge of the inner side walls being spaced from said inner surface of said front wall and forming therewith and with the inner surfaces of the intermediate side walls a staple driver passage, said base wall having a staple ejecting passage, a staple strip guide within said casing, and staple driving means within said driver passage adapted to drive a staple from said ejecting passage.

7. In a stapling device, a casing comprising a member of U-shaped cross-section constituting a base wall and side walls, a second member of U-shape in cross-section constituting a front wall and side walls, a third member of U-shape in cross-section constituting a top wall and side walls, the respective side walls of two of said members being engaged at each side of the respective side walls of the other member, means

securing together said members, the forward edges of the intermediate side walls being engaged with the inner surface of said front wall, and the forward edge of the inner side walls being spaced from said inner surface of said front wall and forming therewith and with the inner surfaces of the intermediate side walls a staple driver passage, the forward edge of said base wall being recessed and constituting with the inner surface of said front wall a staple ejecting passage, a staple strip guide within said casing, and staple driving means within said driver passage adapted to drive a staple from said ejecting passage.

8. In a stapling device, a handle member having side walls and a lower anvil jaw, a pivot shaft extending between said side walls, and a second handle member having a lever extending between said side walls and pivoted on said shaft, an upper jaw casing member opposed to said anvil jaw also pivotally mounted on said shaft, a staple strip guide carried by said casing member, and staple driving means carried by said casing member and adapted to be actuated by said lever, said lever extending into said casing member and being enclosed thereby.

9. In a stapling device, an upper handle member having side walls and a lower anvil jaw, and a lower handle member having a lever extending between said side walls and pivoted thereto, an upper jaw casing member opposed to said anvil jaw also pivotally mounted on said side walls, a staple strip guide carried by said casing member, said lever extending into said casing member, and staple driving means carried by said casing member directly engaged by said lever and adapted to be actuated by said lever to move downwardly relatively to said casing member as said lower handle member is pressed upwardly toward said upper handle member.

EARL C. BUNNELL.
